UNITED STATES PATENT OFFICE.

BERNARD ARTHUR BEHREND, OF NORWOOD, OHIO, ASSIGNOR, BY MESNE ASSIGNMENTS, TO THE BULLOCK ELECTRIC COMPANY, A CORPORATION OF OHIO.

DYNAMO-ELECTRIC MACHINE.

SPECIFICATION forming part of Letters Patent No. 783,398, dated February 21, 1905.

Application filed November 24, 1903. Serial No. 132,448.

To all whom it may concern:

Be it known that I, BERNARD ARTHUR BEHREND, a citizen of the United States, residing at Norwood, in the county of Hamilton and State of Ohio, have invented certain new and useful Improvements in Dynamo-Electric Machines, of which the following is a full, clear, and exact specification.

My invention relates to dynamo-electric machinery, and particularly to means for ventilating and cooling that type of machine in which revolving field-magnets are used.

The ventilating and cooling of the windings of a dynamo and those parts heated by eddy-currents is usually accomplished by dividing the core of the windings into sections and forming air-spaces between them. Another method is to force air over the parts to be cooled either by an air-blast from an outside source or by a special blower or fan mounted on the shaft.

By my invention the advantages of both of the above methods are combined and part of the machine itself serves as the blower or fan, and I so construct the other parts that a plentiful supply of air is furnished to that part of the machine serving as the blower. Moreover, by my invention the amount of air supplied is not only plentiful, but it is directed to the parts where it is most necessary in a very efficient manner.

In the revolving field type of dynamo-electric machine the seat of the greatest amount of heating is in the stationary winding and its core. The revolving field-windings and field-poles are also heated to some degree; but the heating of these parts is ordinarily not excessive, due mainly to the fact that in revolving the free circulation of the air about them keeps their temperature low. The stationary windings and frame are not, however, cooled to any appreciable degree by the flow of air across and around the field-magnets, as such flow of air is not directed radially. Neither does it suffice to provide ventilating-passages through the field-magnets, as the flow of air is then restricted by the small width of the passages, as well as their excessive length, which length includes not only the length of the

50 pole, but the depth of the frame as well. Furthermore, in providing ventilating-spaces in the field-magnets, the width of the pole is correspondingly increased, which results in more copper being necessary for the field-coils, with a consequent greater resistance of the windings. 55 By my invention I provide ventilating-spaces in the stationary core and also in the rim of the revolving field-frame. The ventilating-spaces in the latter are provided solely for the purpose of giving an abundant supply of air to the spaces between the poles. The size of such ventilating-spaces is not limited as in the case of field-magnets, and mechanical strength and sufficient area for the magnetic flux need only be considered. In 60 my construction the air is forced outwardly against the stationary winding and core and through the ventilating-spaces therein, partly 65 on account of the action of centrifugal force, but mainly by reason of the fact that the 70 field-magnets act as fans and drive the air outwardly.

My invention will be better understood by reference to the following description and accompanying drawings, which show the preferred form of construction, and the novelty 75 thereof will be definitely set forth in the claims.

Figure 1 is an outline of a large alternating-current machine, which is a type of machine to which my invention is particularly applicable. Fig. 2 is an enlarged sectional view on line 2 2 of Fig. 1, and Fig. 3 is a sectional view on line 3 3 of Fig. 2.

The stationary frame 1 is built up of the yoke 2, made in box form and provided with 85 numerous openings 3 on the sides. The yoke is divided into sections by the partitions 2', which have the holes 3' formed therein. The stationary core is built up of laminated sections 4, which are spaced apart by separators 90 5. The laminæ are dovetailed into the inner enlarged portions 6 of the partitions 2'. The separators 5 may be made in any approved manner and as shown are made up of radial ribs 7, connected by thin cross-strips 8, and 95 have projections 9, which dovetail into the cross portions 6. The laminations are clamped between the end plates 10 by the bolts 11.

The armature-winding 12 is located between the teeth of the core and secured in place in the usual manner. The end connections of the winding are covered and protected by the shields 13, secured to the yoke.

The revolving field-frame comprises the arms 14 and the rim-segments 15. These segments carry cross-bars 16 integral therewith and which project some distance outwardly from the periphery of the segments. Dovetailed upon the cross-bars 16 are the laminated sections 17, separated from each other by ribbed separators 18, similar to the separators used in the stationary frame. The separators are likewise dovetailed onto the cross-bars 16. Into the periphery of the laminated sections 17 are dovetailed the field-poles 19, provided with the field-windings 20. The poles are built up of laminae clamped together by the bolts 21. The sections 17 are bolted together between the plates 22, and over these are secured the cover-plates 23. It will be noted that the sections 17 are supported some distance from the segments 15, there being a clear space 24 between them.

When the machine is in operation, air is drawn in through the spaces 24, as indicated by the arrows in Fig. 2, and then passes through the wide ventilating-spaces between sections 17 out between the poles. The air is then forced radially against the inner periphery of the stationary frame and out through the spaces between sections 4 to the yoke, where it passes out through the holes 35. In this way the air is circulated through the parts where it is most desired in a very efficient manner, and the air-passages can be made of ample size. As the air is supplied from the interior of the field-frame to the spaces between the poles it is forcibly fanned through the stationary frame, the field-magnets thus serving as the blades of a fan.

Although I have shown and described a specific embodiment of my invention, I wish it understood that I am not limited to the exact construction shown. For example, various forms of separators may be used, as well as the means for securing the poles in place; also the poles could be bolted directly to the rim of the revolving frame and openings made in the rim between the poles, and other modifications could be developed, without departing from the spirit of my invention.

I claim as my invention—

1. In a dynamo-electric machine, the combination of a revolving field-frame and a stationary frame, said field-frame having a series of poles arranged in a circumferential direction on its periphery and ventilating-spaces, through the rim of said field-frame and communicating with open spaces between said circumferentially-arranged poles, the poles

acting as fans to force the air drawn through the rim toward the stationary frame, substantially as described. 65

2. In a dynamo-electric machine, the combination of a revolving field-frame and a stationary frame, said field-frame having a series of poles arranged in a circumferential direction on its periphery, and ventilating-spaces through the rim of said field-frame, and communicating with open spaces between said circumferentially-arranged poles, the poles acting as fans to force the air drawn through the rim toward the stationary frame, and said stationary frame being also provided with ventilating-spaces, substantially as described. 75

3. In a dynamo-electric machine, the combination with a revolving field-frame, and a stationary frame, said field-frame having a series of poles arranged in a circumferential direction on its periphery, and ventilating-spaces through the rim of said field-frame, and communicating with open spaces between said circumferentially-arranged poles, the poles acting as fans to force the air drawn through the rim toward the stationary frame, and said stationary frame comprising a yoke having openings and laminated sections carried by said yoke spaced apart for the purpose of ventilation, substantially as described. 80

4. In a dynamo-electric machine, the combination of a stationary armature-frame having openings for the purpose of ventilation and a revolving field-frame having open spaces between the field-magnets, said field-frame comprising a rim made up of segments carried by the arms of the frame and sections supported by said segments some distance therefrom, said sections being spaced from each other, the field-magnets acting as fans to force the air drawn through the rim toward the stationary frame, substantially as described. 90

5. In a dynamo-electric machine, the combination of a stationary armature-frame having openings for the purpose of ventilation and a revolving field-frame having open spaces between the field-magnets, said field-frame comprising a rim made up of segments carried by the arms of the frame, cross-bars on said segments and laminated sections supported by said cross-bars some distance from the segments, said sections being spaced from each other, the field-magnets acting as fans to force the air drawn through the rim toward the stationary frame, substantially as described. 105

In testimony whereof I affix my signature in presence of two witnesses.

BERNARD ARTHUR BEHREND.
